UNITED STATES PATENT OFFICE.

JOHN J. REYNOLDS AND ARTHUR H. JENKINS, OF RULEVILLE, MISSISSIPPI.

DIRIGIBLE BALLOON.

1,291,687.

Specification of Letters Patent. Patented Jan. 14, 1919.

Application filed July 21, 1916. Serial No. 110,525.

To all whom it may concern:

Be it known that we, JOHN J. REYNOLDS and ARTHUR H. JENKINS, citizens of the United States, residing at Ruleville, in the county of Sunflower and State of Mississippi, have invented certain new and useful Improvements in Dirigible Balloons, of which the following is a specification.

The invention has for an object to effect the simplification of propelling and controlling means of aerial craft, and aims particularly to simplify the connections between the motor and a screw propeller. A further important object is to enable attention to be given to adjustment or repair of some of the cylinders of an internal combustion motor while other cylinders are in operation, enabling the propeller to be driven without interruption while adjustments are made. Another important object is to enable the construction of the propeller and engine as a unit, while at the same time enabling the use of the propeller as a steering and controlling device, either for guiding the craft, or for assisting in its ascent or descent. It is a further important object to enable the engineer to remain beside the engine in such a unit, during inclination and turning, and also to enable such engineer to effect the movement of the unit for the effect intended.

It is a further purpose to give a desirable construction in driving connections between the engine and propeller; also to provide an efficient and desirable fuel feeding system.

It is an important purpose of the invention to give a device of this character particularly desirable for use in military craft, whereby liability of complications in connecting the steering mechanism and engine control will be eliminated as far as possible. Also, whereby rapid control and efficient power transmission may be attained.

Additional objects, advantages, and features of invention will appear from the construction, arrangement and combination of parts hereinafter set forth, and shown in the drawings, wherein,

Figure 1 is a perspective view of one embodiment of our invention, in the form of a dirigible balloon, although it is to be understood that the invention may be adapted to use with other crafts of different kinds.

Fig. 2 is a cross sectional view thereof, Fig. 3 is a detail of a pumping device for use therewith, 55

Fig. 4 is a detail plan of an engine-propeller-steering unit,

Fig. 5 is a detail elevation thereof,

Fig. 6 is a fragmentary top view of the supporting frame for the engine units, with 60 a portion broken away, and portions omitted,

Fig. 7 is a detail elevation of the pivot yoke for the engine units,

Fig. 8 is a detail of the engine unit steering control, 65

Fig. 9 is an elevation of a modified arrangement of steering control,

Fig. 10 is a detail plan view of the last named modification.

There is illustrated a craft including twin balloons 11, the gas envelops and structural details of which may conform to the best practice, means being provided, however, for attaching the load at 12 along the outer side of these balloon elements, and 70 at 13 along their inner sides, there being six points of attachment indicated on each side of each balloon element, in the present instance. Suspended from the balloon elements intermediately thereof, there is a car 14 comprising a part of which is the long cylindrical reserve tank 15, which is utilized 75 to form the principal rigid elements of the car. The supporting cables 16 are connected to suitable devices at 17 on the upper side of the tank, in a suitable manner to support the tank and car. Between the balloons 11 there is constructed a plane element 18, extending for the major part of the length of the balloons, which are spaced 80 90 apart principally by the structure of this plane element.

The balloons may be of the sectional type, and in the present instance there are illustrated a plurality of connections 19 to different sections of the balloons, leading from a compressor device 20, centrally located on the craft, and having connections with the tank 15, whereby the gases may be compressed within the tank, when taken from 100 the balloons, or may be delivered from the tank to the balloons, as desired, a by-pass 19' and valve being indicated, and supply connections of ordinary kinds may be made

for these purposes where desired on the tank, the details of which it is not necessary to illustrate.

Individual valves for the balloon sections 3 are located in the leads thereto, as at 21. The valves at 21 are controlled individually by suitable cables 22, extending downwardly and into the car 14. The compressor may be of any desired construction, preferably 10 of some well known form utilizing the diaphragm system, although any desired form 15 of compressor suitable for the purpose may be used.

The car 14 may be of any suitable construction, in which the rigidity of the tank 15 is utilized, and cargo carrying chambers 23 are suspended beneath the car as illustrated, the details of the manner of supporting these chambers, and the manner of attaching the balloons 11 to the load forming 20 the subject of separate applications of even date herewith.

Tanks for fuel and lubricating oil may be located at any convenient points in the car, 25 these not being shown. At the forward end of the tank 15 there is mounted a base frame 24, upon which there is suitably mounted a combined engine, propeller, and steering unit, 25. The frame 24 is formed with suitably broadened plates 26, adapted to be secured upon the forward end of the tank 15, as illustrated in Fig. 5, and is formed with branched arms 27, extending longitudinally of the craft and provided at their extremities with suitable bearings 28, in which there 30 is mounted a vertical shaft 29. The shaft 29 is hollow and provided with a suitable retaining hub or collar 31, at its lower end beneath the lower bearing 28. A yoke 30 on 35 the shaft includes upwardly extending arms 32, having alined horizontal bearings 33 at their extremities through which there is mounted a suitable shaft 34, carrying a platform 35 upon which engine units 36 are mounted. In the present instance, the platform is rectangular in shape and four units 40 36 are mounted thereon, adjacent respective corners of the platform, each unit being in the form of a four cylinder internal combustion motor with its crank shaft arranged longitudinally of the platform. Mounted 45 in a suitable manner centrally of the platform, there is a longitudinal propeller shaft 37, having a propeller 38 of approved form 50 attached to the forward end thereof a distance in advance of the platform. Each engine unit is provided on the forward end of its crank shaft with a suitable automatic clutch operated sprocket 39, from which a 55 silent chain 40 is extended to a suitable sprocket 41 on the shaft 37. In the present instance the shaft 37 is preferably mounted below the platform. The engine units are provided with individual carbureters 42 and 60 throttle controls 43, in order that any one 65

may be cut out of operation at any time, to permit repair thereof, while the others are continued in operation to drive the propeller. It is not essential, however, that the 70 throttle controls be individual for each engine unit, and in the present instance they are shown to be controlled in pairs by the levers 43. Any suitable means for cutting off the current for the ignition, or the fuel supply to each of the engine units may be 75 employed, these details not being material. In the present case, in order to properly supply fuel to the engine, a familiar form of 80 vacuum feed system is employed, consisting of a single auxiliary fuel tank 45, from the upper chamber of which the usual vacuum connections are made at 46 with the intake manifold 48 of each of the engine units, a suitable check valve 47 being incorporated in each branch of the vacuum duct, as shown. 85

A suitable seat 49 is mounted upon the platform centrally thereof, for the accommodation of an engineer, and a housing of any desirable kind 50 is built around the platform, to protect the engineer from the extreme cold ordinarily experienced at great altitudes. The fuel supply to the tank 45 is effected by any well known duct construction, including the pipe 51 to the tank 45, this pipe 51 being shown in the present instance as leading downwardly through the platform 35, adjacent its center, and the pipe extending inwardly toward the tank 15; any suitable swivel connections may be incorporated adjacent the axis of the shafts 95 29 and 34, if desired. By using coiled tubing, adjacent the engine, it is thought that the necessity for swivel connections will be obviated, as in ordinary use, the range of movement of the platform 35 will not be excessive. 100

For the control of the platform 35, to direct the propeller 38 in any direction, means are provided for inclining the platform and turning it, as desired. In the present instance, these include a guide rack 60, mounted upon the upper arm of the base frame 24, and supplementary arms 61, extended from the outer end of the arm 27, at suitable intervals to support the guide member. The guide in the present instance is curved, extending preferably over three quarters of a circle horizontally, and is located principally at the inner side of the frame 24, as shown. A concentric medial 110 slot 63 is formed in the upper side thereof, and below this slot within the guide there are formed upper and lower bearing surfaces 64 and 65, in the form of segments of a circle, in cross section, concentric with each other, there being left spaces 66 and 67, at the inner and outer side of these bearing faces. In the space at the outer side, there is provided a rack 69, extending throughout the length of the guide, and concentric with 115 120 125 130

the bearing faces 64 and 65. Engaged between the bearing surfaces 64 and 65, there is a ball element 70, having a circular series of spur teeth 71 thereon adapted to mesh with the rack 69, the teeth 71 being much less broad than the teeth 69, whereby rocking movement of the ball within the guide is permitted. A turning shaft 72 is fixed in the ball, extending upwardly through the slot 63, and through a slot 73 in the platform 35, for a suitable distance, being provided with a hand wheel 74 at the upper end. Engaged revolubly around the upper end of this shaft 72, there is a threaded shaft 75, extending equal distances above and below the platform 35 when the latter is horizontal, and held against reciprocation on the shaft 72 by means of collars 76, secured on the shaft 72. The shaft 75 is provided with a hand wheel 77 at its upper end, and is engaged by an interiorly threaded sleeve 78, having trunnions 79 at opposite sides parallel to the shaft 34 pivoted in a suitable manner on respective sides of the slot 73. The guide 60 in the present instance is formed in several parts, in order to facilitate assemblage, although various methods of manufacturing may be followed. One side of the slot 63 is formed by a top piece 80, at the outer side, fixed upon a base 81 in which the lower bearing face 65 is formed, and on which the rack 69 is also shown to be formed, although the rack may be separate and attached, if desired. A side piece 82 is secured upon the base piece at the inner side, and forms the inner side of the slot 63, the bearing surface 64 at the upper side being formed on the pieces 80 and 82 as shown.

40 If desired, supplementary controlling means for the platform 35 may be provided, (Fig. 5) which may consist of a pulley 85, secured centrally upon the shaft 29, from which a cable 86 partly wound on the pulley is extended rearwardly, as shown, at each side, so that pulling upon one end of the cable will turn the shaft 29 in one direction, rotating the engine units, and draft upon the opposite end will cause opposite effect. For 45 inclination of the platform 35, cables 87 (Figs. 5 and 7) are extended upwardly through the shaft 29 from its lower end, and then oppositely and outwardly, to respective end portions of the platform 35, to 50 which they are attached, so that by operation of the cables in any well known manner the platform may be elevated at one end or the other.

It will be apparent that by operation of 55 the hand wheel 74 and rotation of the ball 70 the gear portion 71 will drive the ball orbitally and as the force thus applied to the shaft 72 is exerted in a plane coincident with the axis of the trunnions 79, oscillation of 60 the shaft is prevented and rotation of the

platform 35 is produced. It is also evident that at any position of the platform 35, rotation of the wheel 77 will elevate or depress the sleeve 78, which is held against rotation upon the shaft 75, and thereby move the 70 platform 35 upon its horizontal pivot for inclination or leveling, as desired.

In Fig. 9 there is shown a modification of the engine propeller steering unit, in which a platform 35' is mounted for oscillation 75 upon a horizontal shaft 34' carried in up-standing arms 32' of a turn table 90. The engine and propeller unit thus form a device corresponding to those previously described and may be similarly mounted upon 80 the platform 35. The turn table 90 is mounted upon a suitable supporting frame 91 extended outwardly from any suitable structure of the air ship, and is provided at the periphery with worm gear teeth 92, with 85 which there is meshed a suitable worm 93, mounted upon the frame 91 at the side, operable by a shaft 94 extending inwardly over the frame 91, and provided with a hand wheel 95 at its inner end. The outer part 90 of the frame 91 is offset upwardly, so that an engineer may conveniently stand upon the inner lower part of the frame 91 to operate the hand wheel 95. By this means 95 the propeller may be turned around a vertical axis to direct it in any desired direction. For the inclination of the platform 35', cables 96 are extended downwardly from opposite ends thereof and over suitable guide pulleys to a drum 97, upon which they are 100 wound in opposite directions, the drum being operated by means of a hand wheel 98 located adjacent the hand wheel 95, so as to be conveniently operative at the same time, and by the same person. In order to prevent rotation of the turn-table from disturbing the cables 96 unduly, and to permit inclination of the platform 35' at any point in its horizontal rotation, the cables 96 are carried under pulleys 99, located on bracket 105 arms 100 secured upon the turn table 92 at opposite sides, pulleys 101 being mounted adjacent the center of the turn table, over which the cables are carried, and extended downwardly through a suitable opening 102 110 in the center of the turn table. Pulleys 103 are mounted upon the lower side of the frame 91, around which the cables are extended rearwardly, to the drum 97 before mentioned.

115 What is claimed is:—

1. In an air craft, a main framework, a universally pivoted platform carried thereby, a motor mounted thereon, said platform being of a size and construction to accommodate 120 an engineer whereby an engineer may remain upon the platform during operation of the craft to control and steer the same, a propeller mounted thereon in fixed relation to the platform and motor, operative con- 125

- nections between the propeller and motor, and means operable from said platform co-active between the main frame work and platform to incline and turn the platform.
- 5 2. In an air craft, a body structure to be propelled, a support thereon, an element mounted for rotation on a vertical axis thereon, a frame carried by the last named element for pivotal movement on a horizontal axis, a motor unit on the frame, a propeller carried thereby, operative connection between the motor unit and the propeller, a support for a navigator on said frame, means thereadjacent to control the motor unit,
- 10 15 means to rotate the frame on a vertical axis, and means to move the frame pivotally on its horizontal axis, each of the two means last named including manual control means adjacent said support for a navigator on the frame.
- 15 20 3. A motor - propeller - steering unit for aero craft comprising a base frame, a support revoluble thereon upon a vertical axis, a second frame pivoted thereupon for movement on a horizontal axis, a guide element on the base frame concentric with said vertical axis, a rack concentric therewith, a geared element engaged with the guide and rack, and including a shaft revolvably engaged with the second frame against oscillation relatively in the direction of rotation of said support, separate means connected with the second frame to move the second frame pivotally on said horizontal axis, a motor on the second frame, a propeller thereon and operative connections between the propeller and motor.
- 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870
- tion on a vertical axis at all stages of its oscillation, a plurality of engine units mounted in fixed relation to the platform, a propeller revoluble on an axis fixed with respect to the engines, separate connections between each engine and the propeller constructed to permit stopping of any unit while the propeller turns, separate controls for the said units, manually controlled means on the platform to rotate the platform on a vertical axis, and manually controlled means on the platform to move the platform for inclination as desired.
6. In a craft of the character described, a base frame, a vertical shaft rotatable therein having upstanding arms at opposite sides, a steering motor device pivoted thereon, a motor carried thereby, a propeller mounted thereon and connected with the motor in fixed axial relation, a rack element concentric with the vertical shaft, members above and below the rack concentric therewith having bearing faces spaced above and below the rack shaped to form sectors of a circle in cross section, the upper of the members being constructed to form a concentric slot throughout the length of the rack, a ball element slidably engaged between the said bearing faces, a gear element on the ball meshed with the rack, a shaft extended from the ball through said slot connected revolvably with the steering motor device, means to rotate the shaft, and means co-active between the shaft and the steering motor device to draw or bear longitudinally on the shaft at will.
7. In an aero craft of the character described, a body structure, including a main longitudinal hollow cylindrical reinforcement, a motor-propeller-steering unit mounted at one end thereof comprising a base frame having plates conforming to and secured to the sides of the reinforcement, said frame projecting beyond the end of the reinforcement and having vertically spaced horizontal arms, a vertical shaft revolvably mounted therein, a yoke element carried at the upper end of the shaft and bearing on the base frame, a motor and propeller mounted in the yoke for oscillation in a vertical plane, means to turn said shaft, and means to oscillate the motor and propeller as a unit, for the purposes described.
